UNITED STATES PATENT OFFICE.

CHARLES J. AHRENFELDT, OF NEW YORK, N. Y.

DESIGN FOR A PLATE OR SIMILAR ARTICLE.

SPECIFICATION forming part of Design No. 36,250, dated March 24, 1903.

Application filed February 24, 1903. Serial No. 144,921. Term of patent 7 years.

To all whom it may concern:

Be it known that I, CHARLES J. AHRENFELDT, a citizen of the United States, and a resident of New York city, in the county of New York and State of New York, have invented and produced a certain new, original, and ornamental Design for a Plate or Similar Article, of which the following is a specification.

10 In the accompanying drawing referred to herein the figure is a plan view of a plate with my design placed thereon.

An escalloped panel *a*, having a small spheroid ornament *a'* in its interior, forms a centerpiece, from the lower part of which at each side proceeds a spirate leafed ornament *d*, extending above the same, a scroll-like ornament *b*, supplemented by spirals *b'*, extending away from it on an upwardly-curved line, 20 a leafed stem *c*, bearing a flower *c'* at its outer end between *b* and *d*, an ornament *e* of the same character as *d*, and branches *f*, bearing flowers and leaves between *b* and *e*. The ornamentation thus described is repeated a 25 number of times to form a continuous band or border alternated with the ornamentation consisting of a pair of reversely-curved leafed scrolls *g*, a stem and flower *h*, and branches *h'* and the leafed scrolls *i* on either side 30 thereof.

The centerpiece consists of a pair of scroll-like ornaments *j* like *b*, supplemented by spirals *j'* like *b'*. The scrolls are joined at their lower parts and proceed upwardly on divergent lines, and a pair of leafed stems *k*, 35 bearing flowers *k'*, are located between them. From the point where the ornaments *j* are joined a pair of ornaments *l* like *e* proceed downwardly on divergent lines, and located between them is a stem and flower *m* and 40 leafed branches *m'* like *h h'*. Between each ornament *l* and *j* is a leafed stem and flower *n* and branch *n'* like the outer portion of *f*.

The plate *x* is of ordinary form.

This design may be applied to articles other 45 than plates.

What I claim is—

The ornamental design for a plate or similar article substantially as herein shown and described.

Witness my hand, this 30th day of January, 1903, at the city of New York, in the county and State of New York.

CHARLES J. AHRENFELDT.
